UNITED STATES PATENT OFFICE.

CHARLES L. HARRIS, OF OMAHA, NEBRASKA.

CHUTE FOR TRANSFERRING MATERIAL.

SPECIFICATION forming part of Letters Patent No. 511,332, dated December 26, 1893.

Application filed March 15, 1892. Serial No. 425,024. (No model.)

To all whom it may concern:

Be it known that I, CHARLES L. HARRIS, of Omaha, in the county of Douglas and State of Nebraska, have invented certain new and useful Improvements in Chutes for Transferring Grain or other Material from One Car to Another; and I do hereby declare the following to be a full, clear, and exact description of the invention, such as will enable others skilled in the art to which it appertains to make and use the same.

This invention relates to certain new and useful improvements in chutes for transferring grain or other material from one car to another, and has for its object the production of cheap, simple and highly efficient means whereby goods in bulk, such as grain, ore, coal and the like can be readily and easily transferred from one car to another or dumped at any suitable point without much loss of breakage and requiring but little handling.

The invention comprises the detail construction, combination and arrangement of parts, substantially as hereinafter fully set forth and particularly pointed out in the claims.

In the accompanying drawings:—Figure 1 shows in side elevation two cars, one above the other, connection being established between the two to permit contents of the upper car being conveyed to the lower car. Fig. 2 is an end view showing two cars at different heights to one side of each other. Fig. 3 is an enlarged detail view of the receiving end of chute. Fig. 4 illustrates the chute connected with the loaded car.

Referring to the drawings, A, A', designate two freight cars, the former in Fig. 1 being shown directly over the latter, while in Fig. 2 it is shown on the top of a hillside, car A' being at the bottom of such hillside. The car to be unloaded of goods in bulk, such as grain, lime, crushed ore, &c., is run onto the elevated track, while the car to which the goods are to be transferred is on the lower track.

B is a chute or conveyer, which is designed to be secured over the lower portion of the door-opening in the elevated or loaded car, and its other, discharge-end placed through the opening in the lower, or empty car, where-

by the contents of the former can be readily conveyed to the latter.

In the present instance this chute or conveyer is shown as being composed of a series of sections b loosely united together by pivoted links b'. These sections are circular and of approximately cone - shape, save the innermost section b² which is of rectangular shape at its outer, receiving portion. 60

C is a widened or receiving section designed to be connected to the car to be unloaded, and to which the flexible leg or chute is secured. In general outline it tapers toward its outer end, and its sides d are flared outwardly at their inner ends and beveled off on their inner edges so as to fit flush against the side of the car. The inner end of bottom d' is flanged, as shown at d², so that it will fit over the bottom of the door-opening and cover rod d³ for guiding the door said rod being connected at its end to the side of the car. To the under side of bottom d' is secured a plate d⁴ which bears against the under side of the car and serves to aid in holding the receiving section in place. To the sides d are pivotally connected hooks d⁵ which are designed to engage guide rod d³ and firmly hold the receiving section in place. The innermost section b² of chute B is connected to the outer end of the flared receiving section by pivoted hook e engaging studs e' projecting from the sides d. 80

In practice the receiving section of the chute or conveyer is readily and easily secured to the loaded car at the side opening thereof, and the lower end of said chute is projected through the opening of the unloaded car. Thus the contents of the former can be readily conveyed to the latter in bulk without having first to unload one car, then elevate the goods and reload a second car, as is now done in transferring bulk car-loads. 90

The advantages of my invention are apparent, and it will be specially observed that by means thereof a great saving in expense of transferring goods is effected, and likewise the loss or breakage consequent upon continuous re-handling is avoided. 95

The chute or conveyer shown and described can be readily and easily attached to a car and the same will be firmly held in place. 100

I claim as my invention—

1. The combination with a car having a side opening therein and a rod d^3 , of a chute or conveyer having a receiving section provided with flared sides and a flanged portion bearing on the bottom of the car, and a plate attached to said receiving section and bearing against the under side of said car and hooks pivoted to said receiving section and designed to engage said rod, substantially as set forth.
2. The herein described flexible chute or conveyer adapted to be employed in loading and unloading cars, consisting of a series of pivotally connected sections, and a receiving section having flared sides arranged to bear

against opposite sides of an opening, a lower d^4 plate d^4 engaging the receiving section, a rod to which said receiving section is pivotally connected, and hooks pivotally attached to said receiving section, and designed to engage said rod, substantially as described.

In testimony whereof I have signed this specification in the presence of two subscribing witnesses.

CHARLES L. HARRIS.
